(57) **CLAIM**

I claim the ornamental design for an outsole, as shown and described.

DESCRIPTION

FIG. 1 is a bottom plan view of an outsole showing my new design;

FIG. 2 is a right side elevational view thereof;

FIG. 3 is a left side elevational view thereof;

FIG. 4 is a front elevational view thereof; and,

FIG. 5 is a rear elevational view thereof.

The broken line in FIG. 1 defines the boundary of the design. The broken lines showing a shoe upper in FIGS. 4 & 5 represent the portion of the design that is not claimed. All of these broken lines and the areas within, form no part of the claim.
